Attorney

UNITED STATES PATENT OFFICE.

LUIS DE FLOREZ, OF POMFRET, CONNECTICUT.

PHONOGRAPH.

Original application filed December 29, 1922, Serial No. 609,604. Divided and this application filed February 20, 1924. Serial No. 694,070.

To all whom it may concern:

Be it known that I, LUIS DE FLOREZ, a citizen of the United States, and a resident of Pomfret, in the county of Wyndham and 5 State of Connecticut, have invented an Improvement in Phonographs, of which the following is a specification.

My invention relates to phonographs and has particular reference to improved turntables used thereon, and is a division of my 10 copending application Ser. No. 609,604 filed Dec. 29, 1922 for phonographs.

The primary object of this invention is to provide a portable phonograph having a 15 turntable so constructed as to permit easy access to the interior of said phonograph, for the purpose of repair, oiling or the like.

Other objects and advantages of this invention will be apparent from the following 20 description, taken in conjunction with the accompanying drawings in which similar characters of reference designate similar parts in the several views;

In the drawings:

25 Figure 1 shows a side elevation partly in section of a phonograph embodying my invention; and

Figure 2 is a fragmentary top plan view of a phonograph embodying my invention.

30 Referring more particularly to the drawings, numeral 1 describes generally a phonograph case which has associated therewith a cover 2, a tone arm 3, a sound box 4, a spring motor 5, the latter mounted in a frame 6, all 35 of which are of any well known construction. Associated with the spring motor 5 and operatively connected therewith by suitable gearing 7, is a driven spindle 8 having a reduced upper end 9, the lower portion of 40 which forms a seat 10.

Mounted on the reduced end 9 of the spindle 8 by any suitable means, such as a lug which engages in a keyway or the like, is an element 11 which element is positioned 45 substantially at right angles to the axis of rotation of the spindle 8, as shown in Fig. 1, the element 11 is supported by a boss or bearing 12, and said element extends a short distance to one side of the spindle (to the 50 left as shown in this figure) forming an extension 11' and extends to the right of the spindle to a point adjacent to the periphery of a turntable 13. At this end, a hinge 14 is provided which hinge is also attached to 55 the turntable 13. The turntable is of con-

ventional construction with the exception that the aperture 15, in the center thereof, is larger than is customary and larger than the reduced end 9 of the spindle 8. Secured to the under side of the turntable is a spring 60 catch 16 which is adapted to cooperate with the extension 11' to hold the turntable 13 in its playing position; a boss 17, surrounding the aperture in the turntable 13, limiting the downward movement of said turntable 65 in an obvious manner.

From the above description it will be apparent that should it be desired to obtain access to the interior of the phonograph for the purposes of adjustment or repair, it is 70 only necessary to swing the turntable on its hinge 14, raising it to approximately the position shown by the dotted lines in Fig. 1 or to any other position allowed by the type of hinge, or pivot, used.

It is believed that the operation of the invention will be fully apparent to those skilled in the art from the above description, taken in conjunction with the accompanying drawings but I desire it understood that, 80 while the drawings illustrate the preferred embodiment of the invention, various changes may be made such as fall within the scope of the appended claims without departing from the spirit of the invention.

What I claim as new and desire to secure by United States Letters Patent is:

1. In a phonograph having a motor, a spindle, and a turntable, means secured to said spindle for supporting and rotating 90 said turntable, said turntable being pivotally connected to said means at a point distant from the center of said table in such a manner that said table may be swung on said pivot whereby the interior of the 95 phonograph is exposed.

2. In a phonograph a spindle, a member rotatable about said spindle, a table rotatable about said spindle, means connecting said member and said table to allow the latter to swing away from the spindle and means secured to said table and engaging the free end of said member for holding said table to said member in operative position.

3. In a phonograph a turn table spindle, a member attached thereto and adapted to rotate therewith and a turntable hingedly mounted on said member and adapted to be swung to and arrested in a position at right angles to the axis of the spindle.

4. In a phonograph a turntable spindle, an elongated member mounted upon the spindle and a turntable hingedly mounted adjacent one extremity of said member at a point adjacent the outer edge of the turntable.
5. In a phonograph a turntable spindle, an elongated member mounted upon the spindle, a turntable hingedly mounted adjacent one end of the member, and adapted to be folded down upon the same to bring the turntable into playing position and means carried by the turntable and so positioned as to resiliently engage the free end of said member and lock the turntable in the playing position.
6. In combination with a phonograph, having a motor, a spindle and a turntable, means secured to said spindle and turntable and permitting the latter to be swung away from its normal position whereby the interior of the phonograph is exposed.

In testimony whereof, I have signed my name to this specification this 19th day of February, 1924.

LUIS DE FLOREZ.
